UNITED STATES PATENT OFFICE.

MARY L. LEONARD, OF ALBANY, NEW YORK.

ADJUSTABLE TABLE.

1,082,884.

Specification of Letters Patent. Patented Dec. 30, 1913.

Application filed June 13, 1912. Serial No. 703,416.

To all whom it may concern:

Be it known that I, MARY L. LEONARD, a citizen of the United States of America, residing at Albany, in the county of Albany 5 and State of New York, have invented certain new and useful Improvements in Adjustable Tables, of which the following is a specification.

My invention relates to adjustable tables, 10 and the object of my invention is to provide a table adapted for use in an automobile which may be adjusted to accommodate the width of the machine; together with such elements and combinations as are herein- 15 after more particularly set forth and claimed.

I accomplish these objects by means of the mechanism illustrated in the accompanying drawing, in which:

20 Figure 1 is a perspective view of an automobile seat showing my table in place. Fig. 2 is a perspective view of the underside of the table with its connections.

Similar letters refer to similar parts 25 throughout the several views.

My table is composed of two leaves, A and B, joined by suitable hinges, C. I also place near the adjoining edges of the leaves a hinged support, D, which may be folded be- 30 tween the leaves when the table is not in use. At one end of each leaf, at each end of the table therefor, when the leaves are extended, I place the adjustable brackets, E, E, adapted to rest upon and engage the 35 side of the arms, F, of the seat, G, as shown in Fig. 1. Each bracket is composed of a single piece of wire curved and bent upon itself, forming two parallel portions, a, b, separated from each other and passing 40 through suitable keepers, d, d, the keepers being secured to the underside of the table leaves, A and B, respectively, near the ends thereof. The curved end of each bracket is

bent at about right angles to the parallel portions, a, b, forming the projecting part, 45 g, g, which engages the side of the arms, F, when in use.

The brackets, E, E, may be drawn out so as to enable the table to be used on an automobile which is wider than the length of 50 the table when the leaves are extended, or the brackets may be pushed in so that they will not extend beyond the table. By curving the ends of the brackets in the manner shown when the two leaves of the table are 55 folded together, the end of one bracket will pass beneath the end of the other and project into and through the parallel portions, a, b, enabling the two leaves to be brought very close together.

What I claim as my invention and desire to secure by Letters Patent is:

A table adapted for use in an automobile, comprising two leaves; suitable hinges connecting the leaves; means for supporting the 65 leaves at or near their point of union, adapted to prevent the leaves from movement on the hinges; a supporting bracket on the end of each leaf adapted to rest upon and engage the side arms of the seat of an auto- 70 mobile, each bracket composed of a single piece of wire curved and bent upon itself, forming two parallel portions separated from each other, the curved end bent at about right angles to the parallel portions 75 forming a projecting part which engages the side of the seat; and means at the end of each leaf for receiving and adjustably holding the parallel portions of said bracket, substantially as described.

In testimony whereof I have affixed my signature in presence of two witnesses.

MARY L. LEONARD.
